PATENTED DEC. 17, 1907.

H. O. MCCLURG.
NON-REFILLABLE BOTTLE.
APPLICATION FILED APR. 5, 1907.

UNITED STATES PATENT OFFICE.

HARRY OGDEN McCLURG, OF BALTIMORE, MARYLAND.

NON-REFILLABLE BOTTLE.

No. 874,021.

Specification of Letters Patent.

Patented Dec. 17, 1907.

Application filed April 5, 1907. Serial No. 366,511.

To all whom it may concern:

Be it known that I, HARRY OGDEN McCLURG, a citizen of the United States, and resident of Baltimore, in the State of Maryland, have made certain new and useful Improvements in Non-Refillable Bottles, of which the following is a specification.

My invention is an improvement in that class of non-refillable bottles which are provided with valved stoppers that permit the discharge, but prevent ingress of liquid. My present invention relates particularly to an improved air-valve attachment of the stopper, that is to say, a valve which with coöperating parts is so constructed and arranged that when the bottle is in normal vertical position it prevents ingress of air, but permits it, when the bottle is inverted, so that the contents which would otherwise be retained in the bottle may be freely discharged.

The details of construction, arrangement and operation of parts are as hereinafter described and illustrated in the accompanying drawing, in which

Figure 1 is a central longitudinal section of a bottle neck with my improved stopper inserted therein, the movable parts being shown in the position they occupy when the bottle is in normal vertical position. Fig. 2 is a similar section, but showing the bottle neck and stopper with the movable parts of the latter in the position they occupy when the bottle is inverted so that air is admitted and the contents of the bottle discharged. Fig. 3 is a perspective view of one of the parts of the stopper. Fig. 4 is a perspective view of the base portion of the stopper. Fig. 5 is a cross section on the line 5—5 of Fig. 1. Fig. 6 is a vertical section on the line 6—6 of Fig. 1.

The bottle neck A is provided in its lower portion with a shoulder 1 and in its upper portion with a circumferential groove 2.

B indicates the cylindrical portion of the body of the stopper, C the base portion thereof, and D the attachment which includes the air valve E—see Figs. 1 and 6.

The upper portion or end of the stopper body B is provided with a series of openings 3 for discharge of liquid and ingress of air. The body B is practically a hollow cylinder, although the opening therein may be slightly tapered. It seats upon the part D which in turn rests on the base part C—see Fig. 4—the same having a circumferential shoulder 4

that rests upon a packing 6—see Fig. 1—that bears upon the shoulder 1 of the bottle neck. The upper portion of the body B is provided with a circumferential groove in 60 which are arranged two semi-circular ribs 5 that constitute catches for engaging the upper shoulder of the groove 2 formed in the bottle neck. An elastic washer 7, preferably cork, is arranged in the groove behind 65 the catches 5. Dotted lines, Fig. 1, indicate space between the adjacent ends of the semi-circular catches. It will be understood that when the stopper is inserted in the bottle neck, the cork washer 7 is compressed until 70 the catches 5 slide down to and enter the groove 2 in the bottle neck, with which the elasticity of the washer will then hold them engaged, so that the stopper cannot be withdrawn.

The base portion C of the stopper is provided with a vertical hollow or tubular extension 8 having an opening 9 in its flat vertical face. A valve 10 composed of some thin resilient material, preferably mica, is arranged in contact with the face of part 8, and covers the opening 9 therein. It may be held in place by various means, it being only requisite that its upper portion shall be left free to open by pressure of liquid when the bottle is inverted, as shown in Fig. 2. In this instance it is shown secured between the base of part 8, and a portion of the part D shown detached in Fig. 3. Such part consists of a flat plate having a segmental opening adapted 90 to receive the projecting portion 8 of the base C. The air valve or the parts composing the same form an attachment of this plate D. The air valve E is shown conical in form and seated in a corresponding seat from which a 95 passage 11—see Fig. 1—leads down through the base C. The stem of the valve projects upward into a tube 12 forming a vertical attachment of the plate or base of part D. Within such tubular portion are arranged a 100 spiral spring 13, and a weight 14, which is in tubular form and encircles the stem. A second spring 15 is interposed between the slideable weight 14 and the head of the valve. Normally, that is to say, when the bottle is in 105 vertical position, the valve is held to its seat by the weight 14 which is supported upon the lower spring 15, and the expansion of the upper spring 13.

It will be seen that when the bottle is normally vertical, the air valve E is seated and the mica valve 10 is also seated or closed, as

shown in Fig. 1. But when the bottle is inverted, as indicated in Fig. 2, the weight of liquid entering the passage in the part 8 opens the valve 10 but its discharge would be arrested were it not for admission of air to supply the vacuum in the bottle. This is effected by the weight of the sleeve 14 which in such case slightly compresses the spring 13 so that the valve falls away from the seat thus allowing admission of air past it. The air finds admission through slots 16 in the base of the tube 12, see Figs. 3 and 6. It is apparent that these slots are inaccessible to any tool or instrument that may be introduced from the outside and thus the valve is at all times free from tampering and will operate effectively for preventing entrance of air in the normal position of the bottle but will open when the bottle is inverted.

20 I claim—

1. In a non-refillable bottle the combination with a bottle neck of a stopper having means for holding it in position therein and comprising a part having a passage for air and a passage for liquid and a resilient valve adapted to open by pressure of liquid thereon, and an air vent comprising a valve seated in the air passage in the base of the stopper; a 25 slideable weight applied to the valve, and a spring adapted to press on the weight and made of such tension that when the bottle is inverted the weight is sufficient to compress it and allow unseating of the air valve, substantially as described.

2. In a stopper for non-refillable bottles the combination with a stopper proper having a passage for discharge of liquid and a valve controlling such passage of an air vent formed by a separate passage in the stopper proper, a valve which is normally seated therein, a slideable weight applied to the stem of the valve, a guide in which the weight is arranged for vertical movement, a spring interposed between the weight and the outer

end of such guide and another spring interposed between the weight and the head of the valve, such springs being of slight tension as and for the purpose specified.

3. In a non-refillable bottle the combination with a stopper proper having an air vent 50 and a passage for discharge of liquid and a valve for normally closing said passage, of an air valve which is normally seated in the air vent, and a spring actuated device applied to the valve for holding it normally seated but 55 adapted to yield to allow unseating of the valve when the bottle is inverted, substantially as described.

4. In a non-refillable bottle, the combination with a stopper comprising a practically 60 cylindrical body, a base having a passage for discharge of liquid, and a valve for controlling the same, of a part D which intervenes the base and body of the stopper and is provided with a vertical tube, an air valve whose 65 stem projects into said tube, a weight which is applied to the valve stem and is slideable within the tube, and a spring pressing upon the weight and thereby imposing pressure on the valve, but made of such tension that the 70 weight compresses it to a considerable degree when the bottle is inverted and thus allows the air valve to fall away from its seat, substantially as described.

5. A stopper for non-refillable bottles having an attachment for preventing admission of air under normal conditions and permitting ingress of the same when the bottle is inverted, the same comprising a part having a tube which serves as a guide, a valve whose stem 80 is adapted to slide in such tube, a weight also arranged within the tube and slideable on the valve stem, and springs between which the weight is balanced, substantially as described.

HARRY OGDEN McCLURG.
